FIG. 1

UNITED STATES PATENT AND TRADEMARK OFFICE
Certificate

Patent No. D. 636,648 S

Patented: April 26, 2011

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Anthony Kriz, Lone Tree, CO (US); YaoKun Gui, Shanghai, (CN); Brent Christopher, Portland, OR (US); and Mark Holtan, Centennial, CO (US).

Signed and Sealed this Twenty-first Day of June 2011.
